MACHINE FOR OPERATING ON LASTS

August R. Schoenky, Swampscott, Mass., assignor
to United Shoe Machinery Corporation, Flem-
ington, N. J., a corporation of New Jersey

Original application January 2, 1941, Serial No.
372,749. Divided and this application June 16,
1942, Serial No. 447,234

3 Claims. (Cl. 144—31)

This invention is concerned with machines for providing the bottoms of lasts with bushings to receive jig pins, and the present application is a division of my copending application for Letters Patent of the United States, Serial No. 372,749, filed January 2, 1941 now Patent No. 2,315,548, April 6, 1943.

My former application mentioned above illustrates and describes a machine comprising a group or gang of three rotary drills arranged to bore holes in the bottom of the forepart of a wooden last for the reception of metallic bushings. The machine is provided with means for locating the forepart of a last with respect to the drills, and with means for securing the last in the desired location. It is also provided with a group or gang of tools for inserting bushings into the drilled holes, and with means for supplying the bushings to those tools. The elements of the machine are so organized and operated that bushings are supplied to the inserting tools while the drills bore the holes, after which the drills are withdrawn from the last, the drills and the inserting tools shifted laterally to place the loaded inserting tools in register with the drilled holes, the inserting tools advanced to insert the bushings, the inserting tools withdrawn from the bushings, and the inserting tools and the drills again shifted laterally, but in the opposite direction, to place them in their initial positions.

The present application is concerned chiefly with those features that relate to the means for supplying the bushings to the inserting tools. One of those features provides a safeguard to avoid breaking or bending the raceways that supply the bushings, in the event that one or more of the latter are fouled by the inserting tools or by other bushings that remain on the tools instead of clinging to the last, as when a drill is broken.

Referring to the drawings,

Fig. 1 is a side elevation, partly in section, of that portion of a last-drilling machine which includes means for locating and securing a last for the operations to be performed (see Fig. 5 of parent application);

Fig. 2 is a front elevation, partly in section, of the lower portion of the machine including a cam shaft and power means for driving it (see Fig. 18 of parent application);

Fig. 3 is a front elevation, partly in section, of the middle portion of the machine including the drills, the tools for inserting the bushings, and the carriage on which they are mounted (see Fig. 24 of parent application);

Fig. 4 is a vertical section in a plane from front to rear (see line IV—IV in Fig. 3) including the inserting tools and the means for supplying the bushings, as in Fig. 34 of the parent application;

Fig. 5 is a top plan view, partly in section, of the structure intersected by line V—V in Fig. 4 (see Fig. 37 of parent application);

Fig. 6 is an elevation, partly in section, similar to a portion of Fig. 4 and indicated by line VI—VI in Fig. 5 (see also Fig. 38 of parent application); and

Fig. 7 is a vertical section including a portion of a last and one of the inserting tools in the act of inserting a bushing (see Fig. 40 of parent application).

To facilitate comparison the reference numerals used herein have the same identity as in the parent application.

The frame of the machine comprises a hollow base 50 (Figs. 2 and 3) and a superstructure 54 (Fig. 1) mounted thereon and affixed thereto. As shown in Fig. 3, a horizontal plate 84 is mortised into the upper wall of the base 50 and is affixed thereto by pins 83 and clamping members 85. This plate provides a bed for supporting a group or series of gauges of which three are indicated at 66, 62, and 60 in Fig. 1. Two other gauges omitted from this figure are comprised in the group and correspond respectively to those indicated at 66 and 62. These gauges are grouped to embrace the toe portion of a last L and are formed to provide supporting ledges on which the margin of the bottom of the last is to be seated. They are also provided with upwardly projecting portions that constitute shoulders or abutments to engage the perimeter of the last and thereby establish the desired lengthwise and widthwise location of the forepart.

When a last has been lodged in the gauges, the toe portion thereof is clamped against them by a block 92 that may be brought down by depressing a treadle (not shown). The block 92 is carried by a vertically movable holder 94 provided with a hollow stem or shank 96. The stem is arranged to slide up and down in a bearing formed in the superstructure 54 of the frame and its vertical movements are imparted to it by a lever 110 with which it is connected by parts having provision for adjusting the heightwise initial position of the stem in accordance with the thickness of the toe portion of a last. These connecting parts include a rod 100, a hand wheel 114 affixed to the upper end thereof, a screw-threaded portion 102, a pin 104 through which

the threaded portion 102 extends and in which a complemental screw thread is formed, and a cross pin 98. The stem 96 is bored to provide a bearing for the pin 98 and the latter is bored and provided with a screw thread to engage a corresponding screw thread on the lower portion of the rod 100. This screw thread and that indicated at 102 are oppositely pitched to effect vertical adjustment of the stem 96 with respect to the lever 110 when the rod 100 is turned. The lever derives its operating motion from the treadle above mentioned.

A member 88 supplements the block 92 to steady the last and to brace its heel end against being displaced by upward force exerted against the bottom of the last, first by the drills and thereafter by the tools that insert the bushings. The member 88 is carried by a vertically movable plunger 252 arranged to slide in bearings in a bracket 254 affixed to the frame member 54. A compression spring 262 surrounds the plunger and exerts its force against a knob 260 to maintain the plunger initially in an elevated position, but when the plunger is depressed manually to carry the member 88 into engagement with the last it is prevented from rising by a latch 284 arranged to cooperate with a series of ratchet teeth 282 formed on the plunger. A light spring 286 normally holds the latch in latching position.

Referring to Fig. 3, three rotary drills 56 are arranged in a group below the plate 84 and are adapted to be elevated through holes 532 formed in the plate. Moreover, three tools 58 are also arranged below the plate and in a similar group. While the drills are rising through the holes 532 the tools 58 are elevated through holes 548 in the plate for the purpose of picking bushings B (Fig. 5) from raceways 546. In due course, the drills 56 and the tools 58 descend below the plate 84, the drills having bored holes in the bottom of the last and the tools 58 having been loaded with bushings. When this stage is reached the drills and the loaded tools 58 are all shifted to the left (Fig. 3) and the loaded tools are thus brought into register with the holes 532. Here, they are again elevated, this time to force the bushings into the drilled holes in the last.

The assemblage of drills 56 and tools 58, together with elements for operating them, are mounted on a carriage 456 arranged to be reciprocated horizontally on a track 572. (See also Fig. 4.) The carriage 456 derives its motions from a cam 592 (Figs. 2 and 3) which is one of a series of cams mounted on a shaft 530. A lever 600 shown in Fig. 3 is mounted on a fulcrum pin 602 and comprises an arm 598 and a longer arm 608. The arm 598 is provided with a cam roll 596 that cooperates with the groove 594 of the cam 592 but the arm 608 is connected to the carriage 456 by a link 622 and other parts forming an adjustable connection between the link and the arm. The purpose of this adjustable connection is to regulate the effective length of the arm 608 by moving the link 622 toward or from the fulcrum pin 602 as may be necessary to render the strokes of the carriage exactly equal to the distance between the axes of the drills 56 and the corresponding axes of the tools 58.

The drills 56 are affixed to individual spindles, one of which is indicated at 404 in Fig. 3 and the spindles are all arranged in bearings provided by a vertically movable drill head 432. This drill head is arranged to slide up and down on a track 458 provided by an upstanding bracket affixed to the carriage 456. The upper portions

of the drill spindles are surrounded by sleeves 408 and are thereby braced against lateral displacement. The sleeves 408 are arranged in individual bearings bored through a member 428 which constitutes a portion of the vertically movable drill head. The lower ends of the spindles are journaled in bearings 444 in the head and they are supported by a bottom plate 445, also a part of the drill head. This part of the drill head is connected to the forward end of an operating lever 512 by a link 518 the upper portion of which is flanked by two bosses 520 formed on the plate. The bosses and the link 518 are connected by a pivot pin. The operating lever 512 is mounted on a fulcrum rod 514 and this rod is arranged in bosses 516 formed on the carriage 456. The rear end of the lever 512 is provided with a roll 524 (Fig. 2) that occupies a cam groove 526 when the drills are located at the drilling station. The cam groove 526 is formed in the left hand face of a cam disk 528 carried by the shaft 530. The cam disk 528 is also provided with a cam groove 628 in its right hand face, and this cam groove is utilized to operate the tools 58 at a later stage in the cycle of operations. When the carriage 456 is shifted to the left, after the drilling operation has been completed and the drills withdrawn, it carries the operating lever 512 away from the cam disk 528 and thereby interrupts the operating connection, but at a later stage in the cycle the carriage is returned to its initial position and the cam roll 524 is thereby restored to its position in the cam groove 526.

Referring to Fig. 3, the drill spindles are provided with individual pinions 446, 448 and 450. The pinions 446 and 450 are both engaged and driven by a pinion 452. The latter has splined connection with a vertical transmission shaft 466, the upper portion of which is journaled in a bearing in the drill head 432 and the lower portion of which is journaled in bearings in a gear case 468 affixed to the carriage 456. Rotation of the pinion 450 is transmitted to the pinion 448 by an intermediate pinion 454. All these pinions may travel up and down with the drill head but the transmission shaft 466 does not partake of this up and down movement.

A spiral gear 472 affixed to the transmission shaft 466 is driven by a corresponding gear (not shown) affixed to a horizontal transmission shaft 476, one end of which is journaled in bearings in the gear case 468 and the other end of which has telescopic connection with a continuously rotating driving sleeve 478. This telescopic connection includes splines by which rotation is imparted to the shaft 476. The driving connections between the sleeve 478 and the drill spindles are thus maintained, notwithstanding the horizontal reciprocation of the carriage 456.

The inserting tools 58 are carried up and down by a tool head 500 (Figs. 3 and 4) arranged to slide on a vertical track 502 affixed to the carriage 456. The carriage is also provided with a lever 540 by which the tool head 500 is moved up and down. This lever is mounted on the fulcrum rod 514, and the forward end of the lever is connected to the tool head by a link 542. The rear end of the lever 540 is provided with two cam rolls 538 and 638 (Fig. 2) one at the right-hand side of the lever and the other at the left. When the tool carriage 456 stands in its initial position (Fig. 3) the cam roll 538 occupies a cam groove 536 in the left hand face

of a cam disk 534, but at this stage the cam roll 630 has no contact with any cam and is merely supported in the air. The cam groove 536 elevates the tools 58 far enough to insert them into bushings in the raceways, and thereafter retracts them below the plate 84 before the carriage 456 is shifted to the left. When such shifting occurs, the lever 540 is transferred from the cam disk 534 to the cam disk 528 (Fig. 2) in the right hand face of which a cam groove 628 is provided to receive the cam roll 630. Then, while the tools 58 are in register with the holes previously bored in the bottom of the last by the drills 56, the cam groove 628 elevates the tool head 500 to insert the bushings into the drilled holes and thereafter retracts the tool head 500 to its lower limit of travel. Finally, the carriage 456 returns to its initial position.

Although the up-and-down movements of the tool head 500 are effected positively by the cams 536 and 628, the tools 58 are arranged in individually yieldable holders 488 (Fig. 7) each upheld by a compression spring 506. The stems of the holders 488 extend through the springs and their lower ends are arranged to slide in holes in the portion 510 of the head. Flanges 504 surrounding the holders are normally held against the upper portion 498 of the tool head by the springs.

All the cams mounted on the shaft 530 are affixed thereto with the exception of the cam 592 which reciprocates the carriage 456. This cam is driven at half speed and, accordingly, is not keyed to the shaft. As shown in Fig. 2, the right hand end of the cam 592 is provided with internal gear teeth 742. A gear 736 keyed to the shaft 530 drives a plurality of pinions (not shown) each of which engages the internal teeth 742. These pinions are mounted on the frame 50 and have fixed centers of rotation.

Referring to Figs. 4, 5 and 6, bushings B are stored in a hopper 916 from which they are fed by a rotary brush 924 and emitted through ports from which they gravitate down inclined raceways 546. The delivery ends of the raceways stand initially in register with the tools 58. Each raceway is provided with a spring-pressed finger 964 pivotally mounted thereon and arranged normally to arrest the foremost bushing in a series at the point of delivery but to be deflected to permit that bushing to be picked from the raceway by a tool 58. As shown in Fig. 7 the lower end of each bushing is provided with a flange 487 adapted to be seated against the bottom of a last L when the barrel portion of the bushing is inserted into a hole in the last. When the bushings reach the delivery ends of the raceways they stand on their flanged ends to receive the tools 58 as the latter rise above the plate 84. Once the tools have been inserted into the bushings the raceways are retracted with horizontal movement and the bushings lodged on the tools 58 are thus picked from the raceways with corresponding deflection of the spring pressed retaining fingers 964.

In the event that a drill becomes broken and either fails to drill a hole in the last or leaves its drilling end in the last the bushing lodged on the corresponding tool 58 will remain on the tool 58. Consequently, when this tool next rises through its hole 548, the bushing that remains on it will foul the bushing then at the delivery end of the corresponding raceway. For this reason the raceways are so mounted as to be lifted to the position represented by dotted lines in Fig. 6.

The raceways and the hopper 916 are all affixed to a bracket 918. This bracket is arranged to swing about a vertical shaft 932 by which it is connected to another bracket 968. The bracket 968 is arranged to rock on a horizontal pivot rod 970 by which it is connected to a stationary bracket 972 affixed to the frame element 50. Now, in the event that the delivery ends of the raceways are lifted by any one of the tools 58 the assemblage including the raceways, the hopper and the two brackets 918 and 968 will rock on the horizontal pivot rod 970 to avoid damage to the raceways, and when this occurs the rocking movement of the assemblage will be resisted in a moderate degree by the weight of the assemblage and by a compression spring 1000 interposed between the movable bracket 968 and an upstanding arm 1002 formed on the stationary bracket 972. Moreover, once the delivery end of the raceway has been lifted from its normal position on the plate 84 it will be caught by a latch 1004 (Fig. 6) and thereby supported in its raised position until the obstruction is removed and the latch retracted by an attendant. A light spring is arranged to project the latch under a block 1006 affixed to the bracket 968 when the raceways are lifted. The latch is provided with an upstanding pin 1010 by which it may be retracted to release the raceway assemblage.

Sidewise movement of the raceways is obtained by oscillating the bracket 918 about the vertical shaft 932. The delivery ends of the raceways are normally maintained in register with the centers of the holes 548 by a compression spring 978 (Fig. 5) that surrounds a rod 976 and exerts its force against a nut 984 screwed on one end of the rod. The other end of the spring is seated against a portion of the bracket 968. The rod 976 is connected to the bracket 918 and the latter is thereby drawn against a stop. For this purpose an adjusting screw 986 carried by the bracket 918 is arranged to engage an abutment on the frame element 50.

Retraction of the raceways from the tools 58 is effected by a cam face 1012 (Fig. 2) on the cam disk 534, and a cam roll 1014 (Figs. 2 and 4) mounted on an arm 1016 affixed to the lower end of a vertical rock shaft 1018. The rock shaft is arranged in a stationary lower bearing 1020 and a stationary upper bearing 1022 (Fig. 5) in the bracket 972. An arm 1024 is affixed to the upper end of the rock shaft and its motions are communicated to the bracket 918 by a link 1026. For this connection the bracket 918 is provided with an arm 1028.

The vertical shaft 932 serves not only as a pivotal connection between the brackets 918 and 968 but also plays a part in transmitting rotation from the shaft 530 (Fig. 4) to the brush 924 in the hopper. A gear 930 affixed to the shaft 932 drives a gear 928 affixed to the shaft 926 on which the brush 924 is mounted. Since the shaft 932 and the brackets 918 and 968 may sometimes be required to rock slightly on the horizontal pivot rod 970, the following connections are provided to drive the shaft 932. As shown in Fig. 4, a vertical shaft 942 is journaled in a stationary bracket 944 and is provided with a spiral gear 948 arranged to be driven by a corresponding gear 950 keyed to the shaft 530. The upper end of the shaft 942 and the lower end of the shaft 932 are connected by articulated transmission elements including universal joints 940 and 934 and an intermediate coupling

938 in which the parts are telescopically related.

The cam shaft 530 (Fig. 2) receives rotation from a driving belt 644 arranged to run on the driving member 642 of a frictional cone clutch. The driven member 650 of the clutch is movable axially to the left to engage the driving member but when retracted therefrom it engages a brake ring 652 affixed to the frame 50. Rotation of the driven clutch member 650 is transmitted to the shaft 530 by a gear train 638.

Having thus described my invention, what I claim as new and desire to secure by Letters Patent of the United States is:

1. In a machine for inserting bushings into preformed holes in the bottoms of work pieces, means for securing a work piece in a bushing-receiving position, a bushing-inserting tool formed to project upwardly into a bushing standing on end, mechanism arranged to move said tool up and down, a raceway the delivery end of which is movable laterally to and from the path of said tool and yieldable upwardly in the event of obstruction between it and the tool, and

means for displacing the delivery end of the raceway from said path while a bushing therein is occupied by said tool.

2. In a machine organized as specified in claim 1, latching means arranged to maintain the deliver end of the raceway above its normal level in the event of its being elevated by an obstruction in the path of the tool.
3. In a machine for inserting bushings into preformed holes in the bottoms of work pieces, means for securing a work piece in a bushing-receiving position, a bushing-inserting tool formed to project upwardly into a bushing standing on end, mechanism arranged to move said tool up and down, a raceway movable about a vertical axis to shift its delivery end to and from the path of said tool and movable about a horizontal axis to enable its delivery end to yield upwardly in the event of obstruction between it and the tool, and means for displacing the delivery end of the raceway from said path while a bushing therein is occupied by the tool.

AUGUST R. SCHOENKY.
